UNITED STATES PATENT OFFICE

LEVI REESE H. DICK, OF CHICAGO, ILLINOIS.

WATER-CLOSET SEAT.

1,293,364.

Specification of Letters Patent.

Patented Feb. 4, 1919.

Application filed January 16, 1915. Serial No. 2,630.

To all whom it may concern:

Be it known that I, LEVI REESE H. DICK, a citizen of the United States, residing at Chicago, in the county of Cook and the 5 State of Illinois, have invented a new and useful Improvement in Water-Closet Seats, of which the following is a specification.

My invention relates to improvements in water closet seats in connection with which 10 a commode or receptacle is to be used. The objects of my improvement are:

1st: To provide a holder for a commode or receptacle, that will firmly hold a commode or receptacle to the underside of a 15 toilet or water-closet seat;

2nd: To afford facilities for adjusting a commode or receptacle to the underside of a toilet or water-closet seat;

3rd: To construct a metal holder that 20 may be readily attached to a toilet or water-closet seat.

I attain these objects by the mechanism illustrated in the accompanying drawing, in which—

25 Figure 1 is an elevation of the toilet or water-closet seat, partly in section and side elevation of the metal holder, with a commode or receptacle in place.

Fig. 2 is a view of the underside of the 30 water-closet or toilet seat, with the metal holder attached, as appears without the commode or receptacle.

Similar letters refer to similar parts throughout the several views.

Copies of this patent may be obtained for five cents each, by addressing the "Commissioner of Patents, Washington, D. C."

The seat A (Fig. 1) is a toilet or water- 35 closet seat such as is used for infant chairs and other toilet or water-closets.

The metal holder B is secured to the underside of the seat by means of screws C and washers D. The screws C are of sufficient 40 length that by leaving a portion of the same protruding from the seat A, the holder B through which the screws C pass will have enough play to permit the placing and removing of the commode or receptacle E, 45 the commode or receptacle E being held in place by its rim F and the metal holder B.

I am aware that prior to my invention 50 toilet or water-closet seats have been made with attachments such as hinges for raising and lowering, but I am not aware that my metal holder for commodes or receptacles has been used.

What I claim as new, and desire to secure 55 by Letters Patent is:

The combination with a board having a circular opening therethrough of a clamp on the under side of said board, comprising a rod curved into a circular form and forming more than a semi-circle, the middle part 60 of said rod being coiled to form a spring and said rod having another part between such coil and its free end bent to form a closed loop.

L. REESE H. DICK.
